CONSTANT FREQUENCY GENERATOR

Thomas B. Gibbs, Chicago, Ill.

Application February 4, 1937, Serial No. 123,994

2 Claims. (Cl. 250—36)

My invention relates in general to constant frequency generators, and the object of the invention, generally stated, is to produce a generator having an output frequency of 60 cycles per second, or other standard or desired frequency, which is exact and not subject to hunting or other variations. The generator may be used to operate an electrical master clock, or in connection with watch timing apparatus, or for other purposes where a constant low frequency is necessary.

The invention depends on the known constant frequency characteristic of a crystal, such as a crystal of quartz, when used in an oscillator, as by coupling the crystal to the grid of a triode having a tuned plate circuit. An oscillator of this type, known as a crystal or piezo electric oscillator, has a very constant frequency, but the natural frequency is high; and, while it can be regulated within certain limits, the lower limit in practice is far higher than frequencies on the order of 60 cycles per second.

The problem is presented, therefore, of devising a frequency divider or arrangement, whereby the output of a crystal oscillator may have its frequency reduced to the desired frequency, say 60 cycles per second. According to the invention, this is accomplished by employing a plurality of so-called multi-vibrators in tandem relation and tuned to progressively lower frequencies. If the desired output frequency is 60 cycles per second, the last multi-vibrator is tuned to that frequency, and the crystal oscillator is tuned to a frequency within its natural range which is an exact multiple of 60. The other multi-vibrators are tuned to intermediate frequencies which are also multiples of 60. The multi-vibrators are not constant frequency devices, but the crystal oscillator has a constant frequency and is used to control the first multi-vibrator and keep it in step at a lower frequency. The first multi-vibrator controls the second multi-vibrator to keep it in step at a still lower frequency, and so on, with the result that the constant frequency characteristic of the crystal oscillator is transmitted to the 60-cycle multi-vibrator. The output from this multi-vibrator, having the desired low frequency and the same constancy as the crystal oscillator, may be amplified to any desired extent.

The foregoing states in brief the broad principle employed in the invention. There are numerous difficulties in the way of employing the principle in practice, which, however, have been satisfactorily solved. The broad aspects of the invention, as well as the various features involved in the

solution of the practical problems, will be dealt with in detail hereinafter, reference being had to the accompanying drawings.

In the drawings, Figs. 1, 2 and 3 show the preferred form of the invention. The apparatus is shown in conventional form, and the connections are shown by means of the usual diagrammatic circuit drawings.

Referring to Fig. 1, the reference character 100 indicates a crystal which is suitably mounted in association with the two metal plates 101 and 102. The crystal rests on plate 102, but plate 101 is separated from the crystal a short distance, say a few thousandths of an inch. Associated with the crystal mounting are a heating coil 103 and a thermostat 104, which are provided for the purpose of maintaining the temperature of the crystal at a point somewhat above normal atmospheric temperatures.

The reference character 107 indicates a type 6A6 vacuum tube, which is a double triode, having two plates, two grids, and a common cathode. In discussing this tube, the two halves of the tube will be considered as left and right triodes, for convenience, and the same practice will be followed in connection with other tubes of the same type.

The left triode, tube 107, has its grid 109 directly connected to the upper plate 101 associated with the crystal 100; and the left triode and the crystal, together with the associated parts and circuit connections constitute a piezo electric oscillator. This oscillator includes a grid leak 106, a variable condenser 105 for regulating the shunt capacity across the crystal to adjust its frequency, and means including an inductance 110 and a condenser 111 for tuning the plate circuit. The grid leak 106 may have a value of 2 megohms, the condenser may cover the range of 7 to 50 micro-microfarads, the inductance 110 may have a value of 10 millihenrys, and the condenser 111 may have a capacity of 70 micro-microfarads. These values are given by way of example, and for convenience are noted on the drawings. The same practice is followed throughout the drawings, and representative values are shown wherever such showing will aid in understanding the circuits.

The values of the tuning elements referred to above are of course selected with reference to the oscillator frequency. In the example shown herein the grid circuit, including the crystal 100, is tuned to a fundamental frequency of 108,000 cycles per second by proper proportioning of the parts and by means of condenser 105. In an

oscillator of this type the oscillator will start and its operation is more stable if the harmonics, especially the second harmonic, make up a large portion of the total output, and accordingly the plate circuit is not tuned to the fundamental frequency, but is tuned to a frequency about half-way between the fundamental frequency and the frequency of the second harmonic, say about 162,000 cycles per second. The plate circuit of the left triode also includes a resistor 120, of 60,000 (60M) ohms. A by-pass condenser is indicated at 121.

The plate circuit of the left triode, tube 107, is coupled to the grid 112 of the right triode by means of a resistor 113 and a condenser 114. The right triode functions primarily as a filter to eliminate the harmonics, and to this end the circuit of plate 115 includes a closed resonant circuit comprising inductance 116 and variable condenser 117 and tuned to resonance at a frequency of 108,000 cycles per second. The plate circuit also includes a resistor 118. A by-pass condenser is shown at 119.

The first multi-vibrator MV1 utilizes another type 6A6 tube, indicated by reference character 127. The plate circuit of the left triode includes a resistor 131, and the grid is provided with a grid leak 130. The plate circuit of the right triode includes resistor 133, and the grid has associated with it grid leak 132. The plate 128 of the left triode is coupled to the grid 137 of the right triode by means of a condenser 134, which may have a capacity of 500 micro-microfarads. Similarly, the plate 136 of the right triode is coupled to the grid 129 of the left triode by means of a condenser 135, also having a capacity of 500 micro-microfarads. Thus the grid of each triode is influenced by the plate circuit of the other triode and the device will oscillate in known manner. The frequency is determined by the values of the resistors and condensers and in the case of the first multi-vibrator is as nearly as possible one-sixth the fundamental frequency of the piezo electric oscillator, or 18,000 cycles per second.

The plate circuit of the right triode, tube 107, is coupled to the grid 129 of the left triode, tube 127, or to the first multi-vibrator, by means of a condenser 123 and a resistor 124.

The second multi-vibrator MV2 is similar to the first and includes a type 6A6 tube 147, but the grid leaks have different values and the plate grid coupling condensers 148 and 149 are of greater capacity, whereby the frequency is lower. The frequency of the multi-vibrator 55 MV2 may be, for example, one-fifth the frequency of the multi-vibrator MV1, or 3600 cycles per second.

The multi-vibrator MV1 is coupled to the multi-vibrator MV2 by a condenser 140, which 60 connects the grid of the right triode, tube 127, with the grid of the left triode, tube 147.

The multi-vibrators MV3 and MV4, including tubes 157 and 167, respectively, are similar to the first two, but are tuned to progressively lower frequencies. The frequency of the multi-vibrator MV3 may be one-fifth that of the second, or 720 cycles per second, and the frequency of the multi-vibrator MV4 may be one-half that of the third, or 360 cycles per second.

The multi-vibrator MV2 is coupled to the multi-vibrator MV3 by means of a condenser 150. The multi-vibrator MV3 is coupled to the multi-vibrator MV4 by means of a condenser 160.

Referring now to Fig. 2, the tube 200 is another

type 6A6 double triode, but the plate circuits are independent and the tube functions as two ordinary triodes. Both grids are controlled from the multi-vibrator MV4 through a condenser 170 and a resistor 171, Fig. 1. Each plate circuit includes an inductance of fairly substantial value in addition to a resistor.

The tube 210 and the tube 220, both type 6A6 tubes, together with the associated circuit and tuning elements shown, constitute two final stage low frequency multi-vibrators MV5 and MV6, and are tuned to operate at 72 cycles per second and 60 cycles per second, respectively. These values are, respectively, one-fifth and one-sixth of 360, which is the frequency of the multi-vibrator MV4. The low frequency multi-vibrators are similar to those shown in Fig. 1, except for the difference in frequency.

The plate circuit of the left triode of tube 200 is coupled to the 72-cycle multi-vibrator MV5 by means of condenser 202, and the plate circuit of the right triode of tube 200 is coupled to the 60-cycle multi-vibrator MV6 by a condenser 204.

The reference character 230 indicates a triode which may be a type 76 tube. The grid of this tube is controlled from the multi-vibrator MV5 by means of a voltage divider or potentiometer comprising the resistor 212 and the resistor 231, the latter resistor functioning also as a grid leak and being shunted by a condenser 232. The plate circuit of tube 230 includes a closed resonant circuit comprising inductance 233 and condenser 234 having such values that the circuit is resonant at a frequency of 72 cycles per second. The cathode 236 is not connected direct to ground, but the ground connection includes a resistance 237 shunted by a by-pass condenser 238. The latter may be of the electrolytic type, having a capacity of 10 microfarads or more. The arrangement, including resistor 237, is a customary arrangement for making the cathode positive with respect to ground when the tube passes current, which has the effect of making the grid 225 negative with respect to the cathode 236. In other words, this arrangement provides negative bias for the grid.

The reference character 240 indicates another triode which is similar to triode 230. The arrangement is the same as that just described, except that the closed resonant circuit in the plate circuit is tuned to 60 cycles per second instead of 72 cycles per second. The grid, of course, is controlled by the 60-cycle multivibrator.

From the plate circuits of tubes 230 and 240 extend the 72-cycle and 60-cycle output leads 239 and 249. A tap is taken off the 60-cycle output lead 249, and is connected by the means shown to the grid 251 of tube 250, which may be a type 76 triode. The plate circuit of tube 250 is coupled by means of a transformer 253 to the grid 261 on the input side of tube 260, which as shown is a type 6B5 amplifying tube. This tube has two grids and two plates, and also has two cathodes which are connected by a 10,000 ohm resistance inside the tube. This is a somewhat special type of tube, but its construction is known and is sufficiently indicated in the drawings.

The output leads 239 and 249 extend by way of resistors 270 and 271 and condensers 272 and 273 to the switch S, Fig. 3. In its upper closed position switch S grounds output lead 239 and connects output lead 249 to ground through the voltage control rheostat R. In the lower closed

position of switch S these connections are reversed.

The reference character 304 indicates a potentiometer, which is bridged across the output leads 239 and 249 in series with the resistors 302 and 303. The movable contact of the potentiometer is connected to the grid of the tube 300, which may be a type 59 pentode operating as a triode. This tube has the same arrangement for obtaining a negative grid bias as was described in connection with tubes 230 and 240, Fig. 2.

The plate circuit of tube 300 is coupled by means of a transformer 301 to the push-pull power amplifier comprising tubes 310, 311, 312 and 313. These may be type 2A3 tubes. As clearly shown, tubes 310 and 312 are connected in parallel, and likewise tubes 311 and 313. Grid bias is supplied by means which will be pointed out.

The plate circuits are coupled by means of transformer 320 to the A. C. power output leads 330 and 331. Across these leads may be connected any device that requires a constant frequency power supply. The drawings indicate a motor M.

The apparatus is all operated from an A. C. commercial power line. To this end a plug 350, Fig. 3, may be provided, which can be plugged into any convenient receptacle. A switch S1 serves to extend the connection to the power bus bars 198 and 199.

In Fig. 1, the crystal temperature control arrangement, including heater coil 103, is bridged across the bus bars 198 and 199. Also bridged across these bus bars is the primary winding of the transformer 180. This transformer and the rectifier tube 184 constitute a known type of full-wave rectifier for furnishing plate current to the oscillator and multi-vibrator tubes in Fig. 1, also those tubes to the left of the dotted line in Fig. 2. Winding 181 is the rectifier winding and its mid point, which is the negative pole of the rectifier, is connected to ground. The cathode of the tube 184, which is the positive pole, is connected to the plate supply lead 185, also labeled + in the drawings. A suitable filter is inserted as shown. Winding 182 supplies current for heating the cathode of tube 184; and winding 183 supplies current for the heaters in various oscillator and multi-vibrator tubes in Figs. 1 and 2. The heater connections have been omitted to avoid complicating the drawings, but it will be understood that all heaters labeled X—X are connected to winding 183.

In Fig. 2 is shown another full-wave rectifier comprising transformer 280 and rectifier tube 284. This rectifier supplies plate current to the tubes 250 and 260. Transformer 280 also has a winding labeled Y—Y for supplying heater current to these tubes as indicated.

In Fig. 3 is shown a transformer 380, the primary winding of which may be connected across the bus bars 198 and 199 by means of a switch S2. The transformer has a winding 381 which, together with rectifier tube 384, constitutes a full-wave rectifier for supplying plate current to tubes 300 and 310 to 313, inclusive. A winding 383, whose terminals are labeled Z—Z, furnishes current for the heaters of these tubes as indicated. Transformer 380 has another winding 387 which, together with rectifier tube 386, constitutes a full-wave rectifier for supplying a negative grid bias to the tubes 310—313 of the power amplifier. In this connection it will be noted that the cathode or positive rectifier terminal is grounded, while

the mid point of winding 387, which is the negative terminal, leads by way of a suitable filter and over the conductor 349 to the grid circuits of the power amplifier tubes 310—313.

It will be understood that, while certain specific types of tubes have been mentioned, this is merely by way of information to aid in practicing the invention and is not intended as a limitation or to mean that other types of tubes cannot be used. For instance, wherever a double triode type 6A6 tube is used, two ordinary triodes may obviously be substituted. The same is true as regards the other items of apparatus, including the resistors and condensers whose values have been specifically stated, with the object, however, of merely giving one set of values that has been found to be satisfactory.

The operation of the constant frequency generator shown in Figs. 1, 2 and 3 will now be described. For this purpose it will be assumed that plug 350 is inserted in a commercial A. C. power outlet and that switches S1 and S2 are closed. It will be assumed also that switch S is closed to its upper position. Switches S1 and S2 render active the rectifiers and the temperature control arrangement for the crystal, while switch S associates the 60-cycle output lead 249 with the power amplifier. The rectifiers being in operation, the tubes are supplied with heater and plate current, and the crystal oscillator and the multi-vibrators begin to function. These devices are unstable and begin oscillating spontaneously due to any slight mechanical jar or to a slight fluctuation in the plate supply voltage such as is constantly occurring.

In Fig. 1, the oscillator comprising the crystal 100 and the left triode of tube 107 begins to operate and will settle down to a fixed constant frequency of 108,000 cycles per second as soon as the crystal is raised to the predetermined temperature by the heater 103. It may be assumed that the frequency has already been adjusted at this temperature by means of condenser 105.

As a result of the operation of the oscillator, fluctuating currents flow in the plate circuit of the left triode, and the positive potential impressed on the resistor 113 and on condenser 114 from the plate circuit rises and falls. Accordingly, the condenser 114 charges and discharges in series with the resistor 112, and alternating voltages are impressed on the grid 112 of the right triode. These alternating voltages have a fundamental frequency of 108,000 cycles per second, but as stated before, the harmonics, and especially the second harmonic, are pronounced, and voltages of all these frequencies are therefore impressed on the grid 112. Now the plate circuit of the right triode includes a closed resonating circuit which, as previously mentioned, is tuned to resonate at a frequency of 108,000 cycles per second. This resonating circuit offers very little impedance to plate currents produced by the grid voltages of harmonic frequencies, and consequently such plate currents find a low resistance path to ground through the resonant circuit and by-pass condenser 119 and impress very small voltages on the condenser 123. The resonant circuit does, however, offer a very high impedance to plate currents of the fundamental frequency, and consequently the drop across this impedance, fluctuating with the fluctuations of plate current produced by voltages of the fundamental frequency at the grid 112, is applied to the condenser 123. The effective voltage changes at the condenser 123 therefore are made up of

components of very low amplitude due to the harmonics and a component of high amplitude due to the fundamental frequency. The harmonics are thus effectively eliminated.

The operation of a multi-vibrator such as is shown herein is in general well understood and consequently it will be unnecessary to go into this in detail. The first multi-vibrator MV1 oscillates at a frequency of 18,000 cycles per second; that is, it is so tuned that its natural frequency is 18,000 cycles per second, or as near as may be to that value. If oscillating independently, the frequency would tend to vary somewhat due to temperature, supply voltage changes, etc. When connected as shown in Fig. 1, however, multi-vibrator MV1 receives alternating voltages of a frequency of 108,000 cycles per second due to the charging and discharging of condenser 123 and pulls into step and operates at a frequency of exactly 18,000 cycles per second.

An explanation of just why the multi-vibrator does this is somewhat complicated, and a detailed discussion is unnecessary to an understanding of the invention. It may be stated, however, that in the operation of the multi-vibrator the grid 129 goes alternately positive and negative (grid 137, of course, does the same, the voltage changes being displaced 180° in phase from those of grid 129). The alternating voltages due to the charging and discharging of condenser 123 are impressed on grid 129. These impressed voltages alternately aid and oppose the voltages at grid 129 which are produced by the multi-vibrator operation, as they have six times the frequency of the latter; but as the impressed high frequency voltages are of relatively low amplitude they cannot reverse the multi-vibrator grid voltages except when the latter are changing near the zero line. At these points the impressed high frequency voltages apply a corrective influence. If the multi-vibrator or local grid voltage tends to change too early, due to the multi-vibrator running too fast, the change is opposed each time by the high frequency voltage impressed at that instant and the shift across the zero line is delayed. On the other hand, if the local grid voltage tends to change too late, due to the multi-vibrator running too slow, the high frequency voltage has the effect of speeding up the change each time. The control thus exercised is sufficient to keep the multi-vibrator in step, notwithstanding fairly substantial variations in the frequency at which the multi-vibrator tends to operate.

The second multi-vibrator MV2 is tuned to operate at a frequency of 3,600 cycles per second, which is one-fifth the frequency of the first multi-vibrator. The changing potentials at the grid 137 of the first multi-vibrator cause the condenser 140 to charge and discharge and apply alternating voltages of a frequency of 18,000 cycles per second to the grid 142 of the second multi-vibrator. These control voltages serve to keep the second multi-vibrator in step at exactly 3,600 cycles per second, in the same way as just above described.

In a similar manner the third multi-vibrator MV3 is controlled by the second and is kept in step at a frequency of 720 cycles per second, while the fourth multi-vibrator MV4 is controlled by the third and is kept in step at a frequency of 360 cycles per second.

The operation of the fourth multi-vibrator MV4 causes the condenser 170 to charge and discharge, producing alternating voltages having

a frequency of 360 cycles per second which are impressed on the grids of the double triode 200, Fig. 2. The plate circuit of the left triode of tube 200 is coupled to the multi-vibrator MV5 by means of condenser 202, and consequently the multi-vibrator MV5 receives 360-cycle control voltages which keep it in step at the sub-harmonic frequency of 72 cycles per second. The right triode of tube 200 has its plate circuit coupled to the 60-cycle multi-vibrator MV6 by means of condenser 204, and thus the 60-cycle multi-vibrator is kept in step also.

The tube 200 may be referred to as a buffer tube. Although it has an amplifying function, its main purpose is to couple the fourth multi-vibrator to both the 72-cycle and the 60-cycle multi-vibrators in such a manner that neither one of the latter multi-vibrators can react on the other and interfere with the control exercised by the fourth multi-vibrator.

We may consider now the function of the tubes 230 and 240, one of which is associated with the 72-cycle multi-vibrator MV5 and the other with the 60-cycle multi-vibrator MV6. As the grid 211 of multi-vibrator tube 210 goes alternately positive and negative, alternating currents are produced in the circuit which includes resistors 212 and 231, and alternating voltages are applied to the grid 235 of tube 230. The alternating voltages at grid 211 are characterized by sharp peaks and steep wave fronts, which are undesirable for amplification purposes, and accordingly the resistor 231 is shunted by a condenser 232. This condenser charges in series with resistor 212 when the impressed voltage is rising and discharges in series with resistor 231 when the impressed voltage falls, and has the effect of flattening out the peaks and making the voltage changes less abrupt.

The tube 230 has a negative grid bias when passing current, as already explained, and acts as an amplifier. The grid circuit just described improves the wave form of the input voltage, but it does not eliminate the harmonics, which are therefore amplified along with the fundamental 72-cycle frequency and appear in the plate circuit. In order to eliminate these harmonics, there is a closed resonant circuit comprising inductance 233 and condenser 234 inserted in the plate circuit. This resonant circuit is tuned to 72 cycles per second and offers low impedance to the plate currents of harmonic frequencies and high impedance to plate currents of the 72-cycle or fundamental frequency. Only the latter currents, therefore, result in enough drop to impress voltages of substantial amplitude on the output conductor 239. The closed resonant circuit has another effect which is of importance at this stage, which is to store energy on rising voltages and return it on falling voltages, being effective therefore to further improve the output to such an extent that the wave form of the voltage on conductor 239 beyond the condenser 272 is approximately a sine curve.

The circuit arrangement at tube 240 is the same as that at tube 230, and the operation is the same as that just described, except of course that the output at conductor 249 has a frequency of 60 cycles per second.

A portion of the 60-cycle output may be tapped off through a condenser 254 and a resistor 255 and suitably amplified to provide power of constant 60-cycle frequency for operating a clock, as, for example, a master clock. As shown in

the drawing, the resistor 255 is connected to grid 251 of the amplifying tube 250. The output of this tube is transmitted by means of the transformer 253 to the input side of the power amplifying tube 260, and the output of the latter is coupled to the output leads 267 and 268 by means of the transformer 266. The tubes 250 and 260 function in known manner, and their operation need not be explained in detail. The clock, or other device requiring constant frequency 60-cycle power, is connected across output leads 267 and 268.

Attention may now be directed to the power amplifier shown in Fig. 3. The 72- and 60-cycle output leads 239 and 249 extend through resistances 303 and 302, respectively, to the opposite sides of a potentiometer 304, and they also extend to the movable blades of the switch S. Since the switch is assumed to be in its upper closed position, the 72-cycle output lead 239 will be grounded at the switch. The resistor 270 and condenser 272 prevent overloading the tube 230 under these conditions. The output lead 249 extends to ground over two parallel paths. One path extends through resistor 302, potentiometer 304, and resistor 303 to ground on lead 239, and current flow over this path is effective to impress alternating voltages of 60-cycle frequency on the grid of tube 300. The amplitude of these voltages can be adjusted by means of the potentiometer 304. The second path extends through the switch S to ground at the rheostat R, and is a shunt of the first path which is an additional means provided for regulating the input voltage at tube 300. The rheostat R obviously provides for producing any voltage adjustment from zero to maximum. In practice the potentiometer is used to balance the 72- and 60-cycle outputs and after being once adjusted need not be disturbed, the voltage adjustments being made at rheostat R.

The 60-cycle voltages thus impressed on the grid of tube 200 are amplified by tube 300 in well known manner. The output of tube 300 is coupled to the power amplifier comprising the four tubes 310—313 by means of the transformer 301. The power amplifier under discussion is a typical push-pull class B amplifier and operates in known manner. It will be sufficient to state, therefore, that the plate circuits are coupled by means of transformer 320 to the power output leads 330 and 331, which may be extended to any desired point and afford a source of constant frequency 60-cycle alternating current. This power supply may be used for any purpose as required. The drawings indicate by way of example a motor M, which may be a synchronous motor used to drive watch timing apparatus.

It will be understood that 72-cycle alternating current may be obtained if desired, instead of 60-cycle current, merely by reversing the switch S. This operation grounds the 60-cycle lead 249, and renders the 72-cycle lead 239 effective to apply alternating voltage of 72-cycle frequency to the grid of tube 300.

The reason for providing the switch S2 associated with the rectifier in Fig. 3 will now be apparent also. The power output at leads 330 and 331, Fig. 3, will usually be of intermittent application, whereas the output at leads 267 and 268, being used to drive a clock, must be on continuously. The switch S2 enables the apparatus

in Fig. 3 to be shut down when not needed, without disturbing the operation of the apparatus in Figs. 1 and 2.

The multi-vibrators described may be referred to as of the direct coupled, grid drive, single grid control type. The equipment operates satisfactorily, but is somewhat difficult to adjust at the start. The difficulties are due at least in part to the fact that a low frequency multi-vibrator being controlled or governed by one of high frequency tends to react on the latter and interfere with its operation, which makes it necessary to use rather small condensers for coupling purposes between the successive stages. These small condensers offer greater opposition to the low frequency reactions than they do to the high frequency control, and consequently have the desired selective effect, but they also decidedly limit the control power that can be transmitted through them.

The applicant has found that the undesirable reactions from a low frequency multi-vibrator to the high frequency multi-vibrator by which it is being controlled can be entirely eliminated by the insertion of a buffer tube. An example of this is the tube 200, Fig. 2, which is inserted between the multi-vibrator MV4, Fig. 1, and the two low frequency multi-vibrators, Fig. 2. The tube 200 is primarily provided to enable the output of the fourth multi-vibrator to be split, as already described, but it has the added function of preventing any feedback or reaction from the low frequency multi-vibrators and enables appreciably more power to be used for controlling them. The condensers 202 and 204 therefore may have a capacity of 250 micro-microfarads, whereas the condenser 160, through which the fourth multi-vibrator is controlled, has a capacity of only 70 micro-microfarads. For these reasons it may be stated that coupling the successive stages by means of buffer tubes is somewhat more satisfactory in operation than direct coupling, although it is also more expensive.

The invention having been described, that which is believed to be new and for which the protection of Letters Patent is desired will be pointed out in the appended claims.

I claim:

1. In a frequency divider, a multi-vibrator, two other multi-vibrators operating at different frequencies each of which is a sub-multiple of the frequency of said first multi-vibrator, and space discharge means for causing said first multi-vibrator to control each of said other multi-vibrators independent of the other, said means including grid circuits coupled to said first multi-vibrator and plate circuits coupled to said other multi-vibrators, respectively.

2. In combination, a crystal oscillator of constant high frequency, frequency dividing means comprising a plurality of multi-vibrators in tandem controlled by said oscillator, a plurality of other multi-vibrators having different frequencies, means including a space discharge device whereby the low frequency tandem connected multi-vibrator controls each of said other multi-vibrators independently to keep them in step with said oscillator and at the same time prevent interaction between them, a power amplifier, and switching means for impressing the output of any one of said other multi-vibrators on said power amplifier.
